To all whom it may concern:

Be it known that I, VICTOR N. Figure 1 is a perspective view of the base for a display stand, showing my new design.

Figure 2 is a side view of the same.

The lining in the figures is for the purpose of indicating a contrast which exists between the surfaces which are not lined and those which are shown lined.

I claim:

The ornamental design for a base for a display stand or similar article, as shown and described.

In testimony whereof I have signed my name to this specification.
